13 Claims. (Cl. 8—34)

1

This invention relates to improved reduction baths containing alkali metal hydrosulfite and over-reduction buffers and the compositions for producing them.

In ordinary vat dyeing there is used a reduction bath to transform the vat dye into its leuco form. This reduction bath is strongly alkaline and for the reducing material generally uses a metal hydrosulfite, usually sodium or zinc hydrosulfite. Numerous vat dyes in the past have shown themselves sensitive to over-reduction in dyeing at elevated temperatures. This constituted a serious drawback in the case of the sensitive dyes, as there is a great economic advantage in dyeing at high temperature. In Patents 2,548,543 and 2,548,544, both dated April 10, 1951, and in Patent 2,576,846, dated November 27, 1951, there have been described processes for the high temperature dyeing of vat dyestuffs which are sensitive to over-reduction using certain over-reduction buffers. In the two patents dated April 10, 1951, the inorganic nitrites and halogenates are described and claimed, and in Patent 2,576,846, dated November 27, 1951, organic nitrogen compounds in which the nitrogen is attached by at least one co-valent bond to oxygen and by at least one co-valent bond to an element other than oxygen or nitrogen are described and claimed. These compounds stabilized the dyestuffs and prevented over-reduction. The same compounds were also found to improve the dyeing with certain pyranthrone vat dyestuffs which are not sensitive to over-reduction. Processes using nitrites and halogenates in the dyeing of these pyranthrone dyes are described and claimed in Patents Nos. 2,548,545 and 2,548,546, both issued April 10, 1951, while in Patent No. 2,576,847, issued November 27, 1951, the use of the organic nitrogen compounds referred to above is described and claimed in the dyeing of the pyranthrone dyes.

The stabilizing agents or over-reduction buffers described solve the problem presented by over-reduction of sensitive vat dyestuffs in high temperature dyeing and improve the dyeing of the pyranthrone dyestuffs referred to above. However, this greatly improved result was obtained at the expense of increased hydrosulfite consumption and while the consumption of hydrosulfite is not so great as to render the improved dye processes uneconomical, the cost of the increased hydrosulfite consumption is nevertheless sufficient so that reduction of the excessive consumption is economically desirable.

The mechanism which results in increased hydrosulfite consumption is not fully determined, but appears to be due at least in part to chemical reaction with the stabilizer or over-reduction buffer.

According to the present invention, I have found that if a substantial amount of manganese compound is introduced into the bath, the excessive consumption of hydrosulfite at high temperatures is very greatly reduced and as a result on standing the hydrosulfite concentration is much higher than in the bath contained no manganese ions. It is not known just how the presence of the manganese compound reduces excessive hydrosulfite consumption and therefore the invention is not restricted to a particular theory of how it behaves. It is possible that a manganese salt or complex of the hydrosulfite may be formed which is less reactive with the stabilizers or over-reduction buffers than the alkali salts. However, although this may be a factor, it seems probable that it is not the only factor because manganese ions are effective in amounts very materially less than the stoichiometrical equivalents necessary for forming manganese hydrosulfite.

The preparation of baths has been described above in terms of adding ingredients to the bath. In many cases this is preferable, but it is also possible to produce compositions containing the vat dyestuff and the manganese. Such compositions contain sufficient manganese so that when a vat dye bath is prepared in the normal manner the manganese counteracts the hydrosulfite consumption. Thus, it is possible to market a composition which can be used without any measurement of other ingredients to produce the dye baths of the present invention.

The over-reduction buffers are substantial equivalents and the present invention is therefore applicable regardless of whether there is a single buffer present or a mixture of two or more of them.

While manganese compounds of the present invention may also be used with other compounds having the same effect, namely, magnesium compounds and trialkanolamines, these other compounds are not claimed per se in this case but constitute the subject matter of the copending applications of Jerry M. Mecco, Serial No. 258,281, filed November 26, 1951, and Serial No. 258,282, filed November 26, 1951, both now abandoned.

The operation of the present invention is not limited to vat dyeing baths in which the vat dye is actually incorporated into the bath. Similar savings in hydrosulfite consumption are obtainable when the bath contains only the stabilizing

2

3

agent or over-reduction buffer and the hydrosulfite as in the case of certain pigment dyeing processes.

The invention will be described in greater detail in conjunction with the following specific examples, the parts being by weight unless otherwise specified.

Example 1

A dye bath was prepared to contain 400 parts of a solution composed of the following materials: 10.0% 30° Bé. caustic soda, 0.75% sodium nitrite, 8.7% of a 1% dispersion of a commercial paste of the vat dye having Color Index No. 1113, 80.55% water.

To this were added 4 parts of a 5% solution of manganous chloride ($MnCl_2 \cdot 4H_2O$). The bath was heated to the boil and then 12.5 parts of sodium hydrosulfite were added.

The temperature was maintained at the boil for 23 minutes, at which time the bath was found still to contain 5 parts of hydrosulfite as determined by titration with a standard indigo solution. At the end of 30 minutes, a swatch of 80 x 80 bleached unmercerized cotton print cloth was introduced into the bath and dyed for 10 minutes at the boil. The result was an excellent strong blue dyeing.

In a similar bath which contained no manganese salt, the hydrosulfite concentration during the dyeing period decreased to less than 1.2 parts in 10 minutes' time, and no hydrosulfite remained after 18 minutes. A swatch of cotton cloth, similar to the above, which was introduced into the bath at the end of 30 minutes remained essentially undyed.

Example 2

The procedure of Example 1 was repeated except only 3 parts of the manganese chloride solution were used. The bath contained 3.6 parts of hydrosulfite after 23.5 minutes and the cotton cloth introduced at the end of 30 minutes became strongly dyed as compared to a control dyeing which was essentially undyed.

Example 3

The procedure of Example 1 was repeated except only 2 parts of the manganese chloride solution were used.

After eleven minutes, the bath still contained 8.5 parts of hydrosulfite whereas a similar bath without the manganese salt had less than 1.2 parts of hydrosulfite after 10 minutes.

Example 4

A dye bath was prepared to contain 4 oz./gal. sodium hydroxide, 4 oz./gal. sodium hydrosulfite, 1 oz./gal. sodium nitrite, 0.1 oz./gal. of a commercial paste of the blue vat dye having Color Index No. 1113 and 0.25 oz./gal. of hydrated manganese chloride. The rate of hydrosulfite consumption at the boil was approximately 0.16 oz./gal./min. In a corresponding bath with no manganese salt present, the hydrosulfite consumption was more than twice as rapid.

Example 5

A dye bath (having no dye present) containing 4 oz./gal. sodium hydroxide, 1 oz./gal. sodium nitrite, and 4 oz./gal. sodium hydrosulfite was held at a temperature of approximately 200° F. The hydrosulfite consumption amounted to approximately 0.3 oz./gal./min. In a corresponding bath which contained, in addition 0.12 oz./gal. of hydrated manganous chloride, the rate

4

of hydrosulfite consumption was only about 0.1 oz./gal./min.

Example 6

A dye bath which contained 4 oz./gal. sodium hydroxide, 0.1 oz./gal. sodium nitrite, 4 oz./gal. sodium hydrosulfite, and 0.1 oz./gal. of a commercial paste of the orange vat dye having Color Index No. 1098 was heated to approximately 200° F. for 30 minutes. At the end of this time, the hydrosulfite content was approximately 3.3 oz./gal. and 1 oz./gal. sodium nitrite was then added. The hydrosulfite consumption then became about 0.7 oz./gal./min.

Example 7

The procedure described in Example 6 was repeated except the bath contained, in addition, 0.2 oz./gal. hydrated manganese chloride. The hydrosulfite consumption in this case was only about one-fourth as rapid as under the conditions of Example 6.

Example 8

The procedure described in Example 7 was repeated except that the dye used was the pink vat dye having the formula: 6,6'-dichloro-4,4'-dimethyl - 2,2'-bis(thio) naphthene indigo. The hydrosulfite consumption was approximately the same as that observed under the conditions described in Example 7.

Example 9

A dye bath containing 4 oz./gal. of sodium hydroxide, 1 oz./gal. of sodium nitrite, 0.08 oz./gal. of a commercial paste of the green vat dye having Color Index No. 1101, and 0.07 oz./gal. manganese sulfate technical grade was heated to approximately 200° F. and 4 oz./gal. sodium hydrosulfite were then added. The rate of hydrosulfite consumption in this bath was only about one-half as great as in a corresponding bath which contained no manganese salt.

A piece of 80 x 80 bleached unmercerized cotton cloth introduced into the bath at the end of 30 minutes and dyed for 10 minutes became heavily dyed. A piece of similar cloth introduced into the corresponding bath which contained no manganese salt remained undyed.

Example 10

The procedure of Example 9 was repeated using manganese resinate instead of manganese sulfate. The results were generally similar to those described in Example 9.

Example 11

The procedure of Example 9 was repeated using 0.03 oz./gal. hydrated manganese chloride instead of the manganese sulfate.

The results were generally similar to those described in Example 9.

Example 12

The procedure of Example 9 was repeated using 0.01 oz./gal. hydrated manganese chloride instead of the manganese sulfate. Again, a good dyeing was obtained with the bath which contained the manganese salt.

Example 13

A dye bath which contained 4 oz./gal. NaOH, 0.1 oz./gal. of a commercial paste of the blue vat dye having C. I. No. 1113, 2 oz./gal. of hydroxylamine hydrochloride and 0.01 oz./gal. of hydrated manganese chloride was heated to approximately 200° F. and 4 oz./gal. of sodium hy-

drosulfite added. At the same time a second bath was prepared in exactly the same way except no manganese salt was added. The rate of hydrosulfite consumption, as measured by titration with standard indigo, was over twice as fast in the bath which contained no manganese as it was in the bath to which the manganese salt had been added.

A swatch of 80 x 80 cotton introduced into the first bath at the end of eleven minutes became 10 heavily dyed while a swatch introduced at the same time into the bath to which no manganese had been added remained essentially undyed.

Example 14

A bath which contained 4 oz./gal. of NaOH, 0.04 oz./gal. of a commercial paste of the blue vat dye having C. I. No. 1113 and 2 oz./gal. of NaClO₃ was heated to approximately 200° F. and 4 oz./gal. of sodium hydrosulfite added. The rate of hydrosulfite consumption in this bath was approximately 0.19 oz./gal./min. In a corresponding bath to which 0.01 oz./gal. of hydrated manganese chloride had been added the hydrosulfite consumption was less than one-half as great.

Example 15

In a bath prepared as described in Example 14 but with no dye present, the rate of hydrosulfite consumption was approximately 0.22 oz./gal./min. without the manganese and only about one-half that fast in the bath which contained the manganese salt.

Example 16

A bath which contained 4 oz./gal. of NaOH and 2 oz./gal. of hydroxylammonium sulfate was heated to about 200° F. and 4 oz./gal. of sodium hydrosulfite added. The rate of hydrosulfite consumption, measured by titration with a standard indigo solution, was approximately 0.33 oz./gal./min. In a corresponding bath to which had been added 0.01 oz./gal. of hydrated manganese chloride the hydrosulfite consumption was only about 0.22 oz./gal./min.

Example 17

Two dye baths were set up, each containing 4 oz./gal. of NaOH, 1 oz./gal. of NaNO₂, 0.1 oz./gal. of a commercial paste of the blue vat dye having C. I. No. 1113 and 4 oz./gal. of zinc hydrosulfite. One of the baths contained, in addition, 0.03 oz./gal. of hydrated manganese chloride.

Titrations with standard indigo showed that, in the bath which did not contain the manganese compound, the hydrosulfite consumption was about 50% more rapid than it was in the other bath in which the manganese ions were present.

Example 18

A dye bath was prepared to contain 4.0 oz./gal. NaOH, 0.03 oz./gal. of a commercial paste of the blue vat dye having Color Index No. 1113, 1.0 oz./gal. NaNO₂, 4.0 oz./gal. sodium hydrosulfite, 0.003 oz./gal. triethanolamine, 0.003 oz./gal. hydrated magnesium sulfate and 0.003 oz./gal. hydrated manganese chloride. When this bath, along with a corresponding bath containing no magnesium, manganese or triethanolamine, was held at a temperature of 200° F., the hydrosulfite consumption was about three times as rapid in the unprotected bath as it was in that which contained the magnesium, manganese and triethanolamine.

Example 19

100 parts of the real dye having Color Index No. 1106 in the form of a press cake were dispersed with 5 parts of disodiumdisulfodinaphthylmethane. To this were added 50 parts of manganeseous chloride after which the mixture was passed through a high speed mixer. This gave a vat dye composition containing the manganeseous salt.

A dye bath was prepared to contain 5 parts of the above paste, 4 oz./gal. NaOH, 1 oz./gal. sodium nitrite and 4 oz./gal. sodium hydrosulfite. When cotton was dyed in this dye bath at a temperature of 200° F., the rate at which the hydrosulfite was consumed was less than the rate of consumption in a similar dye bath in which no manganeseous salt was present.

Example 20

20 The following dye mixtures were prepared using 100 parts of the dye having Color Index No. 1106 in the form of a dispersed press cake as in the preceding example:

100 parts dye—25 parts manganeseous chloride
100 parts dye—12 parts manganeseous chloride
100 parts dye—6 parts manganeseous sulfate
100 parts dye—3 parts manganeseous sulfate

When these were dyed on cotton by the procedure of Example 19, good blue shades were obtained.

If desired, the dyes having Color Index Nos. 1112, 1113, 1098, 1101, may be used in place of the dye having Color Index No. 1106.

Example 21

40 100 parts of the dye of Example 19 in the form of a press cake were dispersed as in Example 19 and then colloidized by the general procedure of U. S. Patent No. 2,090,511, except that 50 parts of manganese chloride were used to replace 50 parts of cerelose. The product was a colloidized vat dye containing a manganese salt.

This powder was used to make a 5% dyeing by the procedure of Example 19 and no difference was noted.

Example 22

The procedure of the preceding example was repeated except the manganese salt was added to the deflocculated press cake before colloidizing. It was then blended with the requisite quantity of sugar.

Dyes having Color Index Nos. 1106, 1112, 1098, 1101 and 1117 were colloidized by the methods outlined above and in Example 21 and the colloidized powders were substituted for the paste in making dyeings according to the process described in Example 19. The results were satisfactory.

Two dye baths were set up, each containing 4 oz./gal. of NaNO₂, 0.1 oz./gal. of a commercial paste of the blue vat dye having Color Index 1113, and 4 oz./gal. of zinc hydrosulfite. One of the baths contained, in addition, 0.03 oz./gal. of manganese chloride.

70 Titrations with standard indigo showed that, in the bath which did not contain the manganese compound, the hydrosulfite consumption was about 50% more rapid than it was in the other bath in which the manganese ions were present.

Example 23

A dye bath was prepared to contain 50 parts of 75 a 1% slurry of the vat dye having Color Index

No. 1113, 15.8 parts of 30° Bé. NaOH, 1.5 parts of NaNO₂, 130 parts of H₂O and 2.6 parts of a 3% solution of KMnO₄. This was heated to 196° F. and there were then added 6 parts of sodium hydrosulfite. The bath was stirred frequently while the temperature was held at 197-198° F. The amount of hydrosulfite was determined at intervals by titration with soluble indigo. After 10 minutes a swatch of 80 x 80 cotton was introduced and dyed for 6 minutes. A strong blue color was obtained and after 18 minutes the bath still contained approximately two parts of hydrosulfite.

Another dyebath was prepared as above with the omission of the 2.6 parts of the potassium permanganate solution. After five minutes the hydrosulfite was practically gone. After seven minutes the dye started to precipitate in the bath, and the swatch of cotton introduced at the end of ten minutes and dyed for six minutes remained essentially uncolored.

Example 25

A dye bath was prepared to contain 0.5 part of a commercial paste of the vat dye having Color Index No. 1113 and containing 0.1 part real dye, 6.0 parts of NaOH, 1.5 parts of NaNO₂, 0.12 parts of MgSO₄·7H₂O, 0.078 part of KMnO₄ and 200.0 parts of water.

The bath was heated to approximately 200° F. and held at that temperature. 6.0 parts of Na₂S₂O₄ were added and the bath stirred frequently.

Titration with a standard solution of soluble indigo showed that at the end of 12 minutes there were still approximately 3.5 parts of hydrosulfite remaining in the bath.

A similar bath was prepared omitting the magnesium sulfate and the potassium permanganate and after 10 minutes the hydrosulfite was entirely consumed.

I claim:

1. A reducing bath suitable for high temperature vat dyeing comprising an aqueous solution of caustic alkali and metal hydrosulfite, a stabilizer against over-reduction of vat dyes selected from the group consisting of inorganic nitrites, inorganic halogenates and nitrogen compounds in which a nitrogen atom is attached by at least

one co-*valent* bond to oxygen and by at least one co-*valent* bond to an element other than oxygen or nitrogen and at least 0.0005 mol of a manganese compound per mol of metal hydrosulfite.

5 2. A bath according to claim 1 containing a vat dyestuff capable of over-reduction at elevated temperatures.

3. A bath according to claim 1 containing a pyranthrone vat dyestuff.

4. A bath according to claim 1 in which the stabilizer is alkali metal nitrite.

5. A bath according to claim 2 in which the stabilizer is alkali metal nitrite.

6. A bath according to claim 5 in which the vat dyestuff is a vat dyestuff of the indanthrone series.

7. A bath according to claim 3 in which the stabilizer is alkali metal nitrite.

8. A bath according to claim 1 in which the stabilizer is a nitrogen compound linked by at least one co-*valent* bond to oxygen and by at least one co-*valent* bond to an atom other than oxygen or nitrogen.

9. A bath according to claim 8 containing a vat dyestuff capable of over-reduction at elevated temperatures.

10. A bath according to claim 9 in which the nitrogen compound is a hydroxylamine compound.

11. A bath according to claim 10 in which the vat dyestuff is a dyestuff of the indanthrone series.

12. A bath according to claim 1 in which there is present in addition to the manganese compound at least one compound selected from the group consisting of soluble magnesium compounds and trialkanolamines.

13. A bath according to claim 12 containing a vat dyestuff capable of over-reduction at elevated temperatures.
